UNITED STATES PATENT OFFICE.

FRANK T. WARD, OF NEW YORK, N. Y.

SAFETY ATTACHMENT FOR ELEVATORS.

SPECIFICATION forming part of Letters Patent No. 252,710, dated January 24, 1882.

Application filed November 23, 1881. (No model.)

To all whom it may concern:

Be it known that I, FRANK T. WARD, of the city, county, and State of New York, have invented a new and Improved Safety Attachment for Elevators, of which the following is a full, clear, and exact description.

The invention consists in the combination of devices, as hereinafter described and claimed.

Reference is to be had to the accompanying drawings, forming a part of this specification, in which similar letters of reference indicate corresponding parts in all the figures.

Figure 1 represents a sectional elevation of an elevator of ordinary construction having my safety device attached, and showing the preferred arrangement of the springs. Fig. 2 is a vertical section of the same, taken on the line *x x*, Fig. 1; and Fig. 3 is a cross-sectional elevation taken on the line *y y* of Fig. 1.

20 A A represent the ways or side vertical bars of the frame of the elevator, which are formed with the gutters *a a* in their side edges, and are provided upon their inner faces with the racks *d d*; and B represents the upper cross-head of the car, which is provided with the guide-plates F F, which are provided with the heads *f f*, which run in the gutters *a a* of the ways A A, as shown clearly in Fig. 3.

Upon the under side of the cross-head B of 30 the car are secured the brackets D D, in which are pivoted the toothed cams E E. To the arms *e e* of these cams are attached the rods, arms, or springs *g g*, the adjacent ends of which lap upon each other in the center of the car, and are correspondingly slotted or forked for the passage through them of the lower end of the vertically movable eyebolt G, to which the hoisting rope or chain is attached.

Between the rods, arms, or springs *g g* and 40 the under side of the cross-head B are placed the curved or semi-elliptical springs H, through which the eyebolt also passes. This spring is of such strength that the weight of the car

upon the eyebolt, when the car is suspended by the hoisting rope or chain attached thereto, 45 will compress the spring so that the position of the eyebolt will be such as to hold the cams by means of the rods, arms, or springs *g g* normally out of engagement with the racks *d d*, as shown in Fig. 1, but will instantly draw the 50 eyebolt down through the cross-head, and permit or cause the engagement of the cams with the racks should the hoisting rope or chain give way or break, and thus hold the car.

Instead of using the semi-elliptical springs 55 H, a coiled spring or a rubber spring or weights might be used and accomplish the same result; but the arrangement shown is preferred; and instead of using the racks and making the cams with teeth, the cams might be made plain, 60 with a plain surface to bear against, which construction would do for elevators intended for light work; but for heavy elevators the construction shown and described is the safest, and is therefore preferred.

The guide-plates F F, besides keeping the car from lateral displacement, serve to tie the ways A A together near the cams and to support them against springing when the weight of the car is held by the cams.

Having thus described my invention, I claim as new and desire to secure by Letters Patent—

The combination, with the bars A, having gutters in their side edges and racks on their inner faces, of the cross-head B, having brackets D, and guide-plates with the heads *f f*, the cams E, pivoted in said brackets and having arms *e e*, the springs *g g*, attached to said arms and overlapping each other, the semi elliptical spring H, and the hoisting - rope eyebolt G, 80 passing through cross-head and springs, substantially as shown and described.

FRANK T. WARD.
